FULCRUM LEVER SCALE

Richard J. Serola, Alfred P. Hoover, and Lloyd P. Kissick,
all of 1109 E. Bishop Drive, Tempe, Ariz. 85282

Filed Apr. 7, 1975, Ser. No. 565,477

Term of patent 14 years

Int. Cl. D10—04

U.S. Cl. D10—87

FIG. 3

FIG. 4

FIG. 1 is an exploded, left front and top perspective view of a fulcrum lever scale showing our new design;

FIG. 2 is an exploded, right rear and bottom perspective view thereof;

FIG. 3 is a cross sectional view of the auxiliary weighing platform as seen from line 3—3 and shown in the "in-use" position atop the fragmented stanchion;

FIG. 4 is a cross sectional view of the weighing pan atop the stanchion as seen from line 4—4; and

FIG. 5 is a partial view of the leg of the scale shown in FIGS. 1 and 2 in a different position.

We claim:

The ornamental design for a fulcrum lever scale, as shown and described.
